his Attorney.

UNITED STATES PATENT OFFICE.

ABRAHAM NOVICK, OF NEW YORK, N. Y., ASSIGNOR TO F. L. SCHMIDT COMPANY, OF NEW YORK, N. Y., A CORPORATION OF NEW YORK.

ENVELOP-FASTENER STRIP.

1,274,754.

Specification of Letters Patent. Patented Aug. 6, 1918.

Original application filed September 26, 1916, Serial No. 122,190. Divided and this application filed December 27, 1917. Serial No. 209,052.

To all whom it may concern:

Be it known that I, ABRAHAM NOVICK, a citizen of the United States, and a resident of New York, borough of Manhattan, in the county of New York and State of New York, have invented certain new and useful Improvements in Envelop-Fastener Strips, of which the following is a specification.

This invention relates to envelop fastener strips and particularly to such strips of that class as are adapted to be severed into suitable lengths and provided with tongues and affixed to envelop bodies, for coaction with perforations in the envelop flaps for fastening the flaps to the envelop bodies, respectively.

The object of my improvements is to provide a strip of the class specified of simple construction, which may be manufactured in a continuous length by simple machinery at small expense.

This application is divided out of my pending application Serial Number 122,190, filed September 26, 1916, envelop fasteners.

25. In the drawing accompanying this application I have illustrated the preferred embodiment of my improvements, wherein:—

Figure 1 is a plan view of the strip with portions broken away and another portion turned back to clearly show the several features thereof. Fig. 2 is a similar plan view showing a modification of my improvements. Fig. 3 is another similar plan view showing a further modification. Fig. 4 is a cross section on line 4—4 of Fig. 1. Figs. 5, 6 and 7 are plan views illustrating several forms of fasteners made from the strip of Fig. 1. The scale is the same throughout the figures of the drawing, except that the thicknesses of material in Fig. 4 are somewhat exaggerated to more clearly show the construction.

In the showing of Figs. 1 and 4, my improved fastener strip comprises a strip of sheet material 2, which may be of paper, cloth, or some other suitable stock. This strip is provided with an adhesive 3 on one face thereof. A metal strip 5, preferably materially narrower than strip 2, has folded thereabout a second strip of sheet material 6. Preferably said second strip is approxi-

mately twice the width of said metal strip and has its lateral edges folded over the edges of the metal strip, thereby inclosing said metal strip. Said second strip 6, inclosing said metal strip 5, is then laid lengthwise and preferably positioned midway widthwise said first strip 2, with the faces of the adjoining edge portions of said second strip 6 contacting with and secured to said first strip by adhesive 3.

In the modification of Fig. 2, said second strip 6 is wrapped diagonally about metal strip 5 and is then secured flatwise to strip 2 by adhesive 3.

In the modification of Fig. 3, the metal strip 5 of Figs. 1 and 2 is replaced by wires, herein shown as two, 7 and 8, laid parallel with each other and preferably spaced apart sufficiently to equal the width of the metal strip of Figs. 1 and 2. Said wires are then inclosed by strip 6 and secured to strip 2, similarly to the showing of Fig. 1.

For forming into individual fasteners, see Fig. 5, a short portion of the assembled strip, as of the finished part of Fig. 1, is severed from the main portion of said strip, and the widthwise mid portion of strip 2 to which strip 6 is attached, is separated near one end thereof from the laterally adjoining portions 9 and 10, by cuts or incisions 11 and 12. Preferably these incisions extend one half to two thirds the length of the short portion of strip 2 of Fig. 5. There is thereby formed a prong or tongue 13, comprising a portion of said strip 2, a portion of folded strip 6 and a portion of metal strip 5.

In the showing of Fig. 6, the short portion of the assembled strip is provided with incisions 11 and 12 at each end, whereby opposite tongues 13 and 14 are formed.

In the showing of Fig. 7, the portions 9 and 10 of strip 2 of Fig. 5 are removed, leaving tongue 13 free.

The individual fasteners of Figs. 5, 6 and 7, may be affixed to envelop bodies by moistening adhesive 3.

It will be understood that the several modifications shown in the drawings are illustrative of the general application of my improvements, and that other variations

within the spirit and scope of my invention will appear to those skilled in the art. Also, members 5, 7 and 8, while preferably of metal, may be made of other suitable material.

Having described my improvements, what I claim is:

1. A strip of envelop fastener material comprising a strip of sheet material having an adhesive on one face, a strip of metal narrower than said strip of sheet material, and a second strip of sheet material folded about said metal strip, said second strip of sheet material, carrying said metal strip, being laid lengthwise said first strip of sheet material and secured thereto by said adhesive.
2. A strip of envelop fastener material comprising a strip of sheet material having an adhesive on one face, a strip of metal narrower than said strip of sheet material, and a second strip of sheet material folded about and inclosing said metal strip, said second strip of sheet material, inclosing said metal strip, being laid lengthwise said first strip of sheet material and secured thereto by said adhesive.
3. A strip of envelop fastener material comprising a strip of sheet material having an adhesive on one face, a strip of metal narrower than said strip of sheet material, and a second strip of sheet material folded about said metal strip, said second strip of sheet material, carrying said metal strip, being laid lengthwise and positioned midway widthwise said first strip of sheet material and secured thereto by said adhesive.
4. A strip of envelop fastener material comprising a strip of sheet material having an adhesive on one face, a strip of metal narrower than said strip of sheet material, and a second strip of sheet material folded about and inclosing said metal strip, said second strip of sheet material, inclosing said metal strip, being laid lengthwise and positioned midway widthwise said first strip of sheet material and secured thereto by said adhesive.

sheet material and secured thereto by said adhesive.

5. A strip of envelop fastener material comprising a strip of sheet material having an adhesive on one face, a strip of metal narrower than said strip of sheet material, and a second strip of sheet material, approximately twice the width of said metal strip, being laid parallel to and folded about said metal strip, said second strip of sheet material, carrying said metal strip, being laid lengthwise and positioned midway widthwise said first strip of sheet material and secured thereto by said adhesive.

6. A strip of envelop fastener material comprising a strip of sheet material having an adhesive on one face, a strip of metal narrower than said strip of sheet material, and a second strip of sheet material, approximately twice the width of said metal strip, being laid parallel to and folded about said metal strip, said folded second strip of sheet material, carrying said metal strip, being laid lengthwise said first strip of sheet material and the faces of the adjoining edge portions of said second strip being secured to said first strip of sheet material by said adhesive.

7. A strip of envelop fastener material comprising a strip of sheet material having an adhesive on one face, a strip of metal narrower than said strip of sheet material, and a second strip of sheet material, approximately twice the width of said metal strip, being laid parallel to and folded about said metal strip, said folded second strip of sheet material, inclosing said metal strip, being laid lengthwise and positioned midway widthwise said first strip of sheet material and the faces of the adjoining edge portions of said second strip being secured to said first strip by said adhesive.

In witness whereof, I hereunto affix my signature this 26th day of December, 1917.

ABRAHAM NOVICK.
